DESIGN FOR A COAT

Irving Cohen, New York, N. Y.

Application April 2, 1938, Serial No. 76,245

Term of patent 3½ years

To all whom it may concern:

Be it known that I, Irving Cohen, a citizen of the United States and residing in Manhattan, in the city, county, and State of New York, have invented a new, original, and ornamental Design for a Coat, of which the following is a specification, reference being had to the accompanying drawing, forming part thereof.

Fig. 1 is a front perspective view of a coat showing my new design.

Fig. 2 is a rear view thereof.

The dominant feature of my design resides in the specific quilting on the sleeves of the coat, as shown. The flower cluster on the shoulder of the coat is permanently attached.

I claim:

The ornamental design for a coat substantially as shown and described.

IRVING COHEN.
